US0D1001290S

(12) **United States Design Patent** (10) **Patent No.:** **US D1,001,290 S**
(45) **Date of Patent:** **** Oct. 10, 2023**

(54) **ORAL CARE DEVICE**

(71) Applicant: **Colgate-Palmolive Company**, New York, NY (US)

(72) Inventors: **Scott Demarest**, Loudon, TN (US); **Brian Bloch**, Hillsborough, NJ (US); **Thuan Chong Tan**, Shanghai (CN); **Francis Tatu**, Sea Girt, NJ (US); **Mark Bartlett**, North East, PA (US)

(73) Assignee: **Colgate-Palmolive Company**, New York, NY (US)

(**) Term: **15 Years**

(21) Appl. No.: **29/821,783**

(22) Filed: **Jan. 3, 2022**

Related U.S. Application Data

(62) Division of application No. 29/652,901, filed on Jan. 4, 2021, now Pat. No. Des. 940,328, which is a division of application No. 29/684,802, filed on Mar. 25, 2019, now Pat. No. Des. 908,890, which is a division of application No. 29/610,377, filed on Jul. 12, 2017, now Pat. No. Des. 849,956.

CLAIM

The ornamental design for an oral care device, as shown and described.

DESCRIPTION

FIG. 1 is a front top left perspective view of an oral care device according to the new design;

FIG. 2 is a front top right perspective view thereof;

FIG. 3 is a front bottom left perspective view thereof;

FIG. 4 is a front bottom right perspective view thereof;

FIG. 5 is a rear perspective view thereof;

FIG. 6 is a front view thereof;

FIG. 7 is a rear view thereof;

FIG. 8 is a left-side view thereof;

FIG. 9 is a right-side view thereof;

FIG. 10 is a top view thereof; and,

FIG. 11 is a bottom view thereof.

The broken lines illustrate portions of the oral care device that form no part of the claimed design.

1 Claim, 9 Drawing Sheets
